SAND DELIVERY NOZZLE ASSEMBLY

Harry A. Kilgore, Elmhurst, Ill., assignor to General Motors Corporation, Detroit, Mich., a corporation of Delaware.

Filed Sept. 30, 1963, Ser. No. 312,542
11 Claims. (Cl. 291—46)

This invention relates to a sand delivery nozzle assembly for discharging sand onto a railway rail and more particularly to a sand delivery nozzle incorporating means to discharge material obstructing flow through the interior thereof while also removing ice from the nozzle exterior.

Considerable work has been done in the past to prevent formation of obstructing material in or to provide means for removing obstructions from sand delivery nozzles as commonly used on railway vehicles to maintain traction between the wheels and rails. This obstruction usually results from freezing water and sand being agglomerated and compacted to form a pellet obstructing flow through the nozzle. None of the structures developed as a result of this work has overcome this problem; therefore, the purpose of this invention is to provide a reliable sand delivery nozzle which efficiently removes obstructions from its flow path.

Accordingly, among the objects of this invention are the provision of a sand delivery nozzle assembly which positively dislodges and breaks up obstructions that may form within its flow path, the provision of a sand delivery nozzle which effectively removes ice from its exterior, and the provision of a sand delivery nozzle which is constructed and positioned to hinder entrance of water which can freeze and obstruct the flow therethrough.

The aforementioned objects are accomplished by providing a nozzle having an expandable sleeve member, which under the influence of slightly higher than normal operating operating fluid pressure, expands to dislodge the obstructions and force them through constrictions, such that engagement with the constrictions disintegrates the obstructing material so they may easily exit the nozzle. The nozzle assembly also incorporates a fluid pressure chamber which is pressurized and expanded outwardly to remove ice from its exterior surface. This assembly is further designed to include an orifice of a particular configuration and is formed of a length sufficient to prevent outside water from entering the assembly to an extent the above objects cannot be accomplished.

Referring now to the drawings in which like reference numerals designate like parts throughout the figures there-of and wherein:

FIGURE 1 is a plan view of sand delivery nozzle of the present invention mounted adjacent a railway locomotive wheel.

FIGURE 2 is a cross-sectional assembly view of a preferred embodiment of the invention.

FIGURE 3 is a cross-sectional assembly view of an embodiment of the invention.

FIGURE 4 is a plan view of a modification of a resilient sleeve utilized in the invention.

FIGURE 5 is a plan view of another modification of the resilient sleeve incorporated in the invention.

FIGURE 6 is a cross-sectional assembly view of the preferred embodiment shown in FIGURE 2 further illustrating the resilient sleeve in an expanded operational position.

FIGURE 7 is an end view of FIGURE 2 illustrating a preferred configuration of the nozzle orifice.

FIGURE 8 is an end view of FIGURE 3 showing one configuration of the nozzle orifice.

FIGURE 9 is a partial cross-sectional assembly view of a modification of the invention.

2

Referring now to FIGURE 1 of the drawings, a sand delivery nozzle assembly N is shown adjustably mounted upon a pivotal lever L adjacent railway wheel W. The nozzle assembly N can be positioned to discharge sand upon rail R to prevent slippage between wheel W and the rail as needed.

With reference to FIGURE 2, nozzle assembly N incorporates a guide member 2 which supports a nozzle 4 having a resilient sleeve 6 attached thereto. The resilient sleeve 6 comprises a fastening portion 8 which is folded over machined surface 9 of a hose coupling nipple member 10 as indicated. Hose nipple 10 contains grooves 12 over which a reinforced rubber hose 14 is disposed and clamped by conventional clamping means 16 so that material of the hose member 14 flows into grooves 12 thereby providing a fluid sealed coupling. The nipple member 10 can be integral with guide member 2 or attached by any conventional means as indicated by welds 18.

20 Nozzle member 4 comprises a lip or sleeve portion 20 which overlaps guide member grooves 22 and is rigidly clamped to the guide member by conventional clamping means 24 such that portions of lip member 20 flow into grooves 22 to also provide a fluid tight connection. 25 The nozzle member 4 further comprises a groove 26 which receives a ring 28 for purposes which will be discussed in detail later in the specification. An annular nozzle chamber 30 is formed by the lip 20 and sleeve 6 for an also later described purpose. 30 As is readily apparent from FIGURE 2, nozzle 4 in conjunction with resilient sleeve member 6 provides a fluid passage 32 through the assembly. The resilient sleeve member 6 comprises integral supports 34 which are positioned to define annular spaces 36 between guide member 2 and the sleeve 6. Guide member 2 is provided with an aperture 38 which threadably receives a vent conduit 40.

FIGURE 3 illustrates a modification of the subject invention wherein guide member 2 is modified to comprise a machined surface 42 which receives a conventional clamping means 16 that retains sleeve fastening portion 8 of sleeve member 6. Grooves 44 are provided in surface 42 so that clamping member 16 is readily effective to secure the parts in place. In this embodiment, the resilient sleeve member 6 does not comprise any integral support surfaces and portion 8 does not overlap the guide member.

With reference to FIGURES 4 and 5, further embodiments of resilient sleeve 6 are illustrated wherein a helical supporting surface 46 is shown in FIGURE 4 and a sleeve member 6 comprising bulbous supporting projections 48 is shown in FIGURE 5.

Referring to FIGURE 6, the sleeve member is expandable adjacent support members 34 to form constrictions 50 and expanded portions 52. Nozzle 4 comprises orifice 54 and the lip member 20 is expandable outwardly at 56.

FIGURES 7 and 8 illustrate two possible configurations of nozzle orifice 54. Of course any configuration that will provide proper sand velocity and distribution can readily be employed. An elongated oval orifice 54' shown in FIGURE 8 has provided highly desirable sand patterns as well as proper sand velocity when used with the subject nozzle assembly.

In FIGURE 9 a modification of guide member 2 is shown as assembled. In this embodiment the guide member 2 is composed of a flexible but relatively stiff material compared to that of sleeve 6 and could be constructed from a section of conventional reinforced or wire wound hose. The only requirement is that the guide member must be stiff enough to rigidly support the areas where sleeve 6 engages its interior to provide the desired constrictions in the sleeve. In this arrangement nozzle 4

is bonded to guide member 2 at 60 and is secured to nipple 10 by clamp 62.

In operation, the sand delivery nozzle assembly N receives a supply of sand and air through the reinforced rubber hose 14 and operates with sleeve member 6 in a normal position as illustrated in FIGURES 2 and 3 until an obstruction occurs in fluid passage 32. Presence of an obstruction in passage 32 can be sensed by any conventional means that is capable of actuating a system to supply hose 14 and nozzle assembly N with a fluid having a significantly higher pressure than that utilized during normal operating conditions. Injection of this higher pressure fluid expands the resilient sleeve member 6 as illustrated in FIGURE 6.

With particular reference to FIGURE 6, it is noted that the sleeve supports 34 engage the interior surface of guide member 2 such that the sleeve is expanded into annular spaces 36. Any pressure or any air existing in the annular spaces 36 is forced through vent conduit 40 so that the sleeve member 6 is free to move to its expanded position. If this condition sleeve member 6 comprises a plurality of constrictions 50 which are created at each of the sleeve supports 34. The sleeve expands at 52 between these constrictions and can engage guide member 2 as shown. Nozzle member 4 comprises the previously mentioned groove 26 which receives metallic spring ring 28 to support the nozzle and provide a further constriction 50. The higher air pressure present in conduit 32 dislodges clogged objects or obstructions in the flow line and forces them progressively through the constrictions 50. Application of the higher fluid pressure initially dislodges the obstruction by either expanding the sleeve or by forcing it through a first constriction and then propels it downstream in a tumbling fashion into and through the remaining constrictions 50. Fluid flow in expanded portions 52 tumbles the obstruction against the next succeeding constriction in a non-aligned manner and forces it through such that it is partially disintegrated. Therefore, it is apparent that as a relatively solid obstructing object is moved through the successive constrictions 50, it will eventually be disintegrated to a size capable of being discharged through nozzle orifice 54.

It should be noted that the overlapping sleeve fastening portion 8 is in substantial axial alignment with the thickness of hose nipple 10 both of which comprise a predetermined dimension such that a snug sliding fit is obtained between portion 8, nipple 10 and the reinforced rubber hose 14. A fluid tight connection between the hose and the nipple implements expansion of the sleeve so that a flow obstruction may be efficiently removed.

Nozzle chamber 30, which is disposed between nozzle lip 20 and sleeve 6 immediately adjacent the terminating downstream end 58 of guide member 2, is formed so that the presence of the higher air pressure within passage 32 results in lip annular portion 56 being expanded outwardly to remove any ice present on the exterior surface of the nozzle.

From the above description, it is obvious this invention affords a sand delivery nozzle construction which readily removes material obstructing flow through the nozzle as the resilient sleeve member is expanded within a rigid guide member and the obstructing material is forced against and through a series of constrictions in a piston-like manner to completely disintegrate and discharge such material. Expanded portions 52 of sleeve 6 define barrel-like chambers which create turbulent fluid flow so that the flow obstruction, when loosened, is tumbled to engage the constrictions in a non-aligned manner. The impact of the obstruction against the constriction and the subsequent forcing of it therethrough assures sufficient disintegration for easy discharge through the nozzle. The subject nozzle assembly is readily attached to a railway vehicle and does not involve any abnormal supporting problems. As illustrated in FIGURE 1, the nozzle assembly N is of sufficient length to prevent water entering and

extending the entire length of the resilient sleeve to prevent initial dislodging. It is significant that this nozzle not only provides a positive means of removal of the matter obstructing flow within the nozzle, but it also incorporates an effective means for removing ice from around its exterior discharge area.

I claim:

1. A sand delivery nozzle assembly comprising a rigid guide member, a nozzle member having a resilient sleeve member connected thereto, said sleeve member extending through said guide member in spaced relation to form an annular chamber therebetween, first fastening means sealingly securing the end of said sleeve remote from said nozzle member to said guide member and a supply conduit, and second fastening means sealingly securing said nozzle to said guide member so that said resilient sleeve member may be expanded to dislodge flow obstructing particles from within said sleeve.

2. A sand delivery nozzle assembly as described in claim 1 wherein said resilient sleeve member comprises a plurality of spaced outwardly extending support members on its outer surface which engage said guide member when said sleeve is expanded.

3. A sand delivery nozzle assembly as described in claim 1 wherein said nozzle member comprises expansion means to remove ice from the exterior thereof.

4. A sand delivery nozzle assembly as described in claim 1 wherein said resilient sleeve member comprises a helical outwardly extending support member along the length of its outer surface which engages said guide member when said sleeve is expanded.

5. A sand delivery nozzle assembly as described in claim 1 wherein said nozzle member contains a reinforcing ring.

6. A sand delivery nozzle assembly as described in claim 1 wherein said guide member comprises a vent conduit.

7. A sand delivery nozzle assembly as described in claim 1 wherein said resilient sleeve member comprises a plurality of bulbous support members on its outer surface which engage said guide member when said sleeve is expanded.

8. A sand delivery nozzle assembly as described in claim 1 wherein said nozzle member comprises an elongated oval discharge orifice.

9. A sand delivery nozzle assembly comprising a resilient sleeve member, a nozzle having an elongated oval orifice attached to said sleeve member, a rigid guide member disposed about said sleeve member, a hose coupling member secured to one end of said guide member, said hose coupling member having an annular portion of reduced outer diameter at its free end to receive a folded over portion of said resilient sleeve member so that a supply hose may be snugly received thereover, a lip portion of said nozzle overlying the other end of said guide member, said lip portion and said sleeve member defining an annular chamber adjacent the nozzle end of said guide member, means sealingly clamping said lip portion to said guide member, said nozzle member having an annular groove formed therein, a support ring disposed in said nozzle groove, a plurality of support members attached to the outer surface of said sleeve member and engaging the inner surface of said guide member, said support members and said nozzle support ring forming a plurality of flow constrictions when said sleeve member is expanded, and a vent conduit attached to said guide member relieving pressure from the exterior of said sleeve member whereby the application of a predetermined fluid pressure expands said sleeve member between said support members and forces flow obstructions through said supporting member constrictions so as to disintegrate the obstructions for discharge through said nozzle, said annular chamber being positioned to cause said nozzle to expand outwardly when said sleeve is expanded thereby removing ice from the exterior thereof.

10. A sand delivery nozzle assembly comprising a resilient sleeve member, a nozzle member attached to said sleeve member, a rigid guide member disposed about said sleeve member, a hose coupling member secured to one end of said guide member, said hose coupling member having an annular portion of reduced outer diameter at its free end to receive a folded over portion of said resilient sleeve member, said hose coupling member further having a plurality of annular grooves formed in its exterior surface, said grooves being positioned to receive and retain a resilient supply hose when the hose is firmly clamped thereabout, an annular sleeve portion of said nozzle overlying the other end of said guide member, said annular sleeve portion and said resilient sleeve member defining an annular chamber adjacent the nozzle end of said guide member, said guide member comprising a plurality of grooves beneath said sleeve portion, means sealingly clamping said sleeve portion to said guide member whereby said annular sleeve portion is forced into said grooves, said nozzle member having an annular groove 20 formed therein, a metal support ring disposed in said nozzle groove, a plurality of annular spaced support members attached to the outer surface of said sleeve member and engaging the inner surface of said guide member, said support members and said nozzle support ring forming a plurality of flow constrictions when said resilient sleeve member is expanded, and a vent conduit attached to said guide member relieving pressure from the exterior sur-

face of said sleeve member whereby the application of a predetermined fluid pressure within said sleeve member expands the same between said support members such that flow obstructions are forced through the constrictions and disintegrated for discharge through said nozzle, said annular chamber being positioned to cause said nozzle to expand outwardly when said sleeve is expanded thereby removing ice from the exterior thereof.

10 11. A device as described in claim 1 wherein said guide member is comprised of a reinforced nonmetallic material.
